UNITED STATES PATENT OFFICE.

WILLIAM H. GRAHAM, OF ST. LOUIS, MISSOURI.

DESIGN FOR A BRACKET FOR WASHSTANDS.

SPECIFICATION forming part of Design No. 24,665, dated September 10, 1895.

Application filed August 1, 1895. Serial No. 557,908. Term of patent 14 years.

To all whom it may concern:

Be it known that I, WILLIAM H. GRAHAM, a citizen of the United States, residing at the city of St. Louis, State of Missouri, have invented and produced a new and original Design for a Bracket for Washstands or the Like, of which the following is a specification, reference being had to the accompanying drawing, forming a part thereof.

The drawing is a side elevation of the bracket, showing my design.

The leading feature of my design consists of a ring or circular body surmounting a standard, and from which project laterally-extending arms.

1 is an upright standard having bands 2 and 3 at either end.

4 is a flaring circular base.

5 is a knob at the upper end of the standard, and 6 is a ring surmounting the same.

7 are arms branching from the ring 6, and above and supported on the ring and arms is a plate 8.

I claim as my invention—

The design for a bracket, substantially as 25 herein shown and described.

WILLIAM H. GRAHAM.

In presence of—

STANLEY STOVER,
E. S. KNIGHT.
